(57) CLAIM

We claim the ornamental design for a panel construction for vehicle partition, as shown and described.

DESCRIPTION

FIG. 1 is a rear perspective view of the panel construction for vehicle partition showing my new design.

FIG. 2 is a rear elevational view thereof.

FIG. 3 is a front elevational view thereof.

FIG. 4 is a top plan view thereof.

FIG. 5 is a bottom plan view thereof.

FIG. 6 is right side elevational view thereof.

FIG. 7 is a left side elevational view thereof.

FIG. 8 is a section view in elevation taken along the line 8-8 of FIG. 3 and showing a section thereof.

FIG. 9 is a perspective view of the panel construction for vehicle partition of FIG. 1 shown in isolation for clarity of illustration.

FIG. 10 is a top plan view thereof.

FIG. 11 is a bottom plan view thereof.

FIG. 12 is a front elevational view thereof.

FIG. 13 is a left side elevational view thereof; and,

FIG. 14 is a right side elevational view thereof.

The broken line showings of the foot well, window frame, roll bar, center portion, right side panel and mounting brackets illustrate portions of the panel construction for vehicle partition that form no part of the claimed design.
